UNITED STATES PATENT OFFICE.

WILLIAM MACMURTRIE AND EDWIN H. HOMSHER, OF PHILADELPHIA,
PENNSYLVANIA.

TOOL-HOLDER.

SPECIFICATION forming part of Letters Patent No. 427,335, dated May 6, 1890.

Application filed September 4, 1889. Serial No. 322,959. (No model.)

To all whom it may concern:

Be it known that we, WILLIAM MACMURTRIE and EDWIN H. HOMSHER, of Philadelphia, in the county of Philadelphia and State 5 of Pennsylvania, have invented a new and useful Improvement in Tool-Holders, of which the following is a full, clear, and exact description.

Our invention relates to an improvement 10 in tool holders or handles, and has for its object to provide a handle capable of receiving and holding burnishers of all descriptions, and also files either with or without tangs or shanks, and especially files having their tangs 15 or shanks broken off.

The invention consists in the novel construction and combination of the several parts, as will be hereinafter fully set forth, and pointed out in the claims.

Reference is to be had to the accompanying drawings, forming a part of this specification, in which similar figures of reference indicate corresponding parts in all the views.

Figure 1 is a side elevation of the handle, 25 partly in section, illustrating a tangless file held therein. Fig. 2 is an edge view of the file and a partial vertical section through the handle. Fig. 3 is a transverse section on line xx of Fig. 1. Fig. 4 is a similar section on line yy of Fig. 1.

In carrying out the invention the body of the handle 10 is preferably made of wood and given any suitable or approved contour. The upper portion of the handle is reduced in diameter, whereby a shoulder 11 is formed, and a vertical slot or channel 12 is produced in the said upper reduced portion of the handle, which slot or channel extends downward a distance in the body of the handle, as illustrated in Figs. 1 and 2. The slot or channel 12 is produced in the center of the upper reduced portion of the handle, forming thereby two members A and B, the member A being of greater length than the opposed member B, 40 as best shown in Fig. 2. The handle is fitted with a ferrule 13, which closely hugs the upper reduced portion and rests upon the shoulder 11. This ferrule, when the handle is to be utilized to hold a file 14 having its tang or 45 shank 15 broken, is provided with side pro-

jections 16, adapted to be located, when the ferrule is placed in position, opposite the sides of the slot or channel 12. The ferrule is of such interior contour that it will closely fit the exterior surface of the upper reduced portion of the handle, and the said ferrule is provided with an inner semicircular integral extension or shoulder 17, adapted to rest upon the upper edge of the shorter member B of the handle, as shown in Fig. 2. The inner 60 face of this extension or shoulder is flush with one side wall of the slot or channel 12, whereby when the ferrule is placed upon the handle a diametrical opening 18 is formed therein, registering with the slot or channel 12. In 65 this opening and the slot or channel 12 the end of the file having a broken tang is introduced, and is rigidly held in the handle by a set-screw 19, extending through one side of the ferrule and also preferably through the 70 longer member A to a contact with one side of the file.

It will be observed that by means of a handle constructed as above described a file which would ordinarily have to be thrown away may 75 be provided with a proper handle, and thereby fitted for use. It will also be observed that as the slot or channel 12 extends downward in the body of the handle a file having a perfect tang or shank may be used in connection with the handle, as well as an imperfect file.

Having thus described our invention, we claim as new and desire to secure by Letters Patent—

1. As an improved article of manufacture, a tool-handle comprising a body having an upper reduced end provided with a vertical slot, forming two members, one of which is shorter than the other, a ferrule fitted to the upper 90 reduced portion, provided with an inner extension or shoulder contacting with the upper surface of the reduced member of the body, and a set-screw passed through the said ferrule and the reduced portion of the handle into 95 said slot or channel, substantially as shown and described.

2. In a tool-holder for the purpose described, the combination, with a body portion provided with an upper reduced end, a vertical bore in 100

the said body, and a vertical slot or channel in the upper reduced end registering with the body-bore and forming two upper members of unequal length, of a ferrule adapted to fit 5 over the reduced bifurcated portion of the body, provided with an inner extension or shoulder capable of fitting upon the upper surface of the shorter member, and a set-screw

passed through the ferrule into the said slot or channel, substantially as shown and de- 10 scribed.

WILLIAM MACMURTRIE.
EDWIN H. HOMSHER.
